UNITED STATES PATENT OFFICE.

ANSON HENRY OLIVER, OF ORILLIA, ONTARIO, CANADA.

ICE-SAWING MACHINE.

Application filed September 2, 1924, Serial No. 735,381, and in Canada September 2, 1924.

My invention relates to ice-sawing machines and has for its object to provide a simply and readily constructed machine for sawing grooves in a field of ice, which may 5 be easily operated by one man from either side or the front thereof.

Briefly stated, my invention consists of a wooden sled-like support, carrying a wooden frame on which is mounted a variable speed internal combustion engine, having a relief clutch, and a circular saw, connected to the engine through a universal joint, the frame being adjustably pivoted on its support. Line guides are provided for 10 controlling the direction of the machine after the first cut is made in the field of ice.

The construction and operation of my invention will now be described with reference 20 to the accompanying drawings, forming a part of this specification and in which—

Fig. 1 is a side elevation showing the saw in operative position in the ice field.

Fig. 2 is a plan view partially broken 25 away for the sake of clearness.

Fig. 3 is a section on line 3—3 of Fig. 1.

Fig. 4 is a section on line 4—4 of Fig. 3.

Fig. 5 is a section through the gear housing on the saw mandrel.

30 Referring to the drawings and particularly to Figs. 1 and 2, the sled is made up of wooden runners 1, having half-round steel shoes 2, held together by two beams 3, through which wooden keys 4 are inserted.

35 Pivot blocks 5 are placed lengthwise of the sled at an angle to the runners, secured to the front beam with bolts 6 and to the rear beam, through slots 7 for adjustment, with bolts 8. The wooden frame, mounted lengthwise of the sled and tapering from the front to the rear, parallel with the pivot blocks, projects over the rear end of the sled to support the saw and consists of the side members 9, held together by the cross beams

40 10, 11 and 11¹. Moreover, the sills 9 are connected at the forward end by the gas pipe 12 of the form shown and this connection forms a handle for raising or lowering the saw when in operation.

45 The frame is adjustably mounted on the pivot blocks 5 by means of studs 13, the heads of which are positioned in slots 14, in the sills as shown in Figs. 3 and 4.

50 A saw aligning screw 15, operating by a crank 15¹ is connected at the pivot point by means of an iron plate 16, and operates

in a stationary nut 17, the connection between the screw and the plate being effected by means of the collars 18 as shown in Fig. 4.

55 The engine, preferably a Ford model, is mounted on an incline to the frame of the machine, with the front end lower and supported on beam 10, while the rear end is suspended from the frame with the lugs 19. The engine is connected to the propeller shaft 21 through the universal joint 20, thus permitting the operation of the shaft on an incline while the engine remains in a horizontal position. The propeller shaft 70 is connected through the boxing 22, supported on the cross beams 11 and 11¹, to the driving pinion 23 which operates the crown gear 24 in the gear casing 25, the crown gear being keyed to the mandrel 26, 75 which in turn is keyed to the collar 27. The mandrel 26 is journalled in the sills 9 of the frame.

80 The saw is rigidly supported on the mandrel between the collar 27 and removable collar 28 by means of pins 29, the removable collar being held in place with the nuts 30 and 31, the latter locking the former in place.

85 The saw is provided with teeth which, while in operation, develop a traction power which assists with the movement of the machine. The machine will work either forward or backward and the saw will cut equally well in either direction.

90 An adjustable gauge 32 is attached to the rear end of the frame, near the centre of the saw, for regulating the depth to which the saw may go, and this gauge is adjusted with the thickness of the ice. The lower end of the gauge carries a roller or disc 34 so that it may readily travel upon the surface of the ice. A safety guard 33 secured to the frame covers the top portion of the saw.

95 Extending across the sled and journalled in the runners thereof are two shafts 35 and 36, each carrying a pair of guide plates 37 which may be adjusted lengthwise of the shaft and secured thereto by a set screw 38. The end of each shaft is turned upright 100 at the right hand side of the sled and is connected to a bar 39 which may be moved backward or forward by means of a lever 40, to set the guide plates as desired for directing the movement of the machine over 105 the ice.

110 It will not be necessary to describe in

detail the engine, which as previously stated is preferably of the Ford type, but it will be noted that the fuel tank 41 is mounted on a sheet metal covering 42 which protects the engine. 43 is the engine accelerator, 44 the crank, 45 the radiator and 46 the gear shift or relief clutch. 47 is a grease cup on the housing 22. The bars 51 which support the rear end of the sheet metal covering 42 are 10 extended upwardly to form handles, which may be used to steer the machine from either side. A rod 48 connected to the clutch lever 46 is secured in the cross beam 11 and provided with a spring 49, the tension of which 15 may be adjusted with the nut 50. The tension of this spring is regulated so that the friction of the clutch is counteracted sufficiently to permit slip or release of the clutch when jars or excessive strains occur. Damage 20 to the saw is thus prevented.

The manner of operating my machine will be clear from the description already given. It will be noted that as the engine is mounted on the frame in an inclined position, 25 when the machine is in operation, the engine will be in approximately a horizontal position, thus permitting efficient lubrication of the engine parts, the universal joint enabling the transmission shaft to 30 operate out of direct alignment with the engine.

In addition to the low cost of construction there are distinct advantages in building my machine of wood owing to the temperature in which it is used. The use of a 35 variable speed engine with a relief clutch overcomes the tendency to break the saw and permits greater production. By operating

the saw aligning screw with the lever 15¹ the frame carrying the saw may be readily adjusted on the pivot blocks which may also be adjusted transversely with the slots in the rear beam of the sled. 40

I provide means not shown for locking the machine in balanced position when not 45 in use.

I claim—

1. An ice-sawing machine, comprising a wooden sled having metal-shod runners, a frame adjustably and pivotally mounted on inverted V-shaped wooden blocks, arranged lengthwise of said sled and at an angle to the runners thereof, said blocks being bolted to the front beam of the sled and adjustably secured to the rear beam, a gas engine supported on said frame in an inclined position to adapt it to assume a substantially horizontal position, when the machine is in operation, a circular saw carried by a mandrel which is journaled in the end of said frame and a 60 transmission shaft, adapted to operate in an inclined position, connected to the engine through a universal joint. 55

2. An ice-sawing machine as defined in claim 1 having means to adjust the position of the frame, said means consisting of a screw operated by a crank in a stationary nut and secured to a plate which is connected to a stud at the pivot of one of said blocks. 65

3. An ice-sawing machine as defined in claim 1 having means for adjusting the position of the frame to effect the alignment of the saw and a sheet metal covering for the engine with a fuel tank mounted thereon. 70

ANSON HENRY OLIVER.
